UNITED STATES PATENT OFFICE.

FREDERICK STEINHAUER, OF MADISON, WISCONSIN.

BOAT-FASTENING MEANS.

1,094,610.

Specification of Letters Patent. Patented Apr. 28, 1914.

Application filed June 21, 1913. Serial No. 775,063.

To all whom it may concern:

Be it known that I, FREDERICK STEINHAUER, a citizen of the United States, residing at Madison, in the county of Dane and State of Wisconsin, have invented certain new and useful Improvements in Boat-Fastening Means, of which the following is a specification.

My invention relates to novel means to connect a boat or the like with a pier, landing or other fixed object.

An important object of this invention is to provide means of the above mentioned character, which will retain a boat or the like in the desired locality while permitting the same to move freely vertically with the waves and laterally therewith for a predetermined degree but preventing the same from moving laterally in either direction beyond a certain distance, the lateral movements of the boat being checked by the apparatus in a most advantageous manner to absorb shocks and jars transmitted to the boat by the waves.

A further object of this invention is to provide means of the above mentioned character, which will yieldingly oppose the slight lateral movements of the boat in opposite directions.

A further object of this invention is to provide means of the above mentioned character, which will prevent the undue longitudinal movement of the boat but permit of the free lateral swinging and reciprocatory movement thereof.

A further object of the invention is to provide means of the above mentioned character, which are simple in construction, strong, durable, cheap to manufacture and easy to connect and disconnect with and from the boat.

Other objects and advantages of this invention will be apparent during the course of the following description.

In the accompanying drawings forming a part of this specification and in which like numerals are employed to designate like parts throughout the same, Figure 1 is a plan view of my improved connecting means, showing the same in use, Fig. 2 is an end view of the same, and, Fig. 3 is an enlarged detail section through a portion of one of the triangular attaching elements.

In the drawings, wherein for the sake of illustration, is shown a preferred embodiment of my invention, the numeral 4 designates a pier or wharf, to which are suitably connected brackets 5, provided with eyes or loops 6, receiving transverse end portions 7 of triangular attaching elements 8. 60 Each triangular attaching element comprises a longitudinally extending tube 9 and a diagonal tube 10, which are connected with the transverse end tube 7 by means of couplings or joints 11, as shown.

The numeral 12 designates a short tube, having one end connected with the end of the longitudinal tube 9 by means of couplings 13 and 13'. The diagonal tube 10 is connected therewith by means of a coupling 14.

The numeral 15 designates a guide sleeve, connected with the short tube 12 by means of a coupling 16. Attention is called to the fact that the guide sleeve 15 and the end 75 of the longitudinal tube 9 of the coupling 13' are spaced, as shown.

Mounted to reciprocate within the longitudinal tube 9 and the guide sleeve 15, as more clearly shown in Fig. 3, is a piston 80 or rod 16, carrying a sleeve 17, clamped thereto by means of a clamping screw or bolt 18, as shown. Surrounding the reciprocatory rod 16 and upon opposite sides of the sleeve or ring 17 are suitably stiff compressible and expansible coil springs 19, the outer ends of which engage the guide sleeve 15 and the coupling 13', as shown. The reciprocatory rods 16 are provided at their outer ends with eyes or apertured 90 heads 20, which receive bolts or pins 21, carried by upstanding brackets 22, preferably attached to the forward and rear ends of a boat 23, as shown. The free ends of the bolts or pins 21 are apertured for receiving pad-locks 24 or the like, whereby the boat is securely connected or locked with the reciprocatory rods 16.

In the use of the apparatus, it is obvious that each of the attaching elements 8 may be 100 swung in a vertical plane and moved horizontally a restricted distance in either direction, whereby the bolts or pins 21 may be easily passed into the openings of the eyes or apertured heads 20. It is obvious that 105 the brackets 22, which are preferably rigidly attached to the boat, are pivotally connected with the rods 16, whereby the boat 23 may swing laterally in either direction. When the boat is reciprocated laterally in 110 either direction, or swung laterally beyond a certain degree, either set of the springs 19

will be compressed, to oppose such movement, depending of course upon the direction of the same. By these means the shocks imparted to the boat by the waves are absorbed with the least damage to the boat.

The apparatus holds the boat in its normal position, and prevents the same from turning around or moving longitudinally beyond a certain degree. In addition to the secure manner in which the apparatus will hold the boat in place, the same may be quickly connected and disconnected with and from the boat. When the boat is disconnected therefrom, the attaching elements 8 may be swung upwardly upon the pier 4.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having described my invention, I claim:—

1. In apparatus of the character described, the combination with a relatively stationary object, of a plurality of spaced triangular open relatively rigid attaching elements, means pivotally connecting the attaching elements with the relatively stationary object, so that such elements may be swung in a substantially vertical plane, reciprocatory rods carried by the attaching elements, means to yieldingly oppose the movement of the rods in both directions, and means to connect the rods with a boat.

2. In a boat securing apparatus, the combination with a relatively stationary object, of a longitudinal tube, means pivotally con-

necting the longitudinal tube with the relatively stationary object, so that the longitudinal tube may be swung in a substantially vertical plane, a guide sleeve spaced from the free end of the longitudinal tube and rigidly connected therewith, a reciprocatory rod mounted within the longitudinal tube and guide sleeve, a sleeve rigidly connected with the reciprocatory rod and disposed between the guide sleeve and the longitudinal tube, coil springs surrounding the reciprocatory rod upon opposite sides of the sleeve carried thereby and engaging said guide sleeve and the longitudinal tube, and means to connect the reciprocatory rod with the boat.

3. A boat attaching apparatus, comprising an open tubular frame, a relatively stationary object, means pivotally connecting one end of the open tubular frame with the relatively stationary object, a reciprocatory rod mounted within a portion of the open tubular frame, spring means to oppose the movement of the rod in both directions, and means to connect the rod with the boat.

4. A boat attaching apparatus, comprising a tube, a relatively stationary object, means pivotally connecting the tube with the relatively stationary object, a rod mounted to reciprocate within the tube, spring means to oppose the movement of the rod in both directions, and means to pivotally connect the rod with the boat.

In testimony whereof I affix my signature in presence of two witnesses.

FREDERICK STEINHAUER.
